COMBINED TOOTHPASTE AND TOOTHBRUSH HOLDER

Robert Shelare, N. Entry Drive, Staten Island, N.Y., and Frank Makara, 29 Orange Drive, Jericho, N.Y.

Filed Aug. 21, 1963, Ser. No. 76,310

Term of patent 14 years

(Cl. D4—3)

FIG. 1 is a perspective view of a combined toothpaste and tooth brush holder showing our new design;

FIG. 2 is a top plan view thereof;

FIG. 3 is a side elevational view thereof, and

FIG. 4 is a bottom plan view thereof.

The toothbrush and toothpaste tube shown in broken lines in respectively FIGS. 1 and 3, are included for illustrative purposes only.

We claim:

The ornamental design for a combined toothpaste and toothbrush holder, as shown and described.
